KITE

Albert J. Torsak, 628 Harpeth Knoll Road,
Nashville, Tenn. 37221

Filed June 2, 1972, Ser. No. 259,363

Term of patent 14 years

Int. Cl. D21—01
U.S. Cl. D34—15 AF

FIG. 1 is a perspective illustration of the kite depicting my new design;

FIG. 2 is an elevational view depicting either side of the kite of my new design;

FIG. 3 is an elevational view depicting the front and rear of the kite taken along lines 3—3 of FIG. 2; and

FIG. 4 is a plan view depicting either the top or bottom of the kite taken along lines 4—4 of FIG. 2.

I claim:

The ornamental design for a kite, as shown and described.
